UNITED STATES PATENT OFFICE

166,477

DECANTER BOTTLE

John A. Margolis, Philadelphia, Pa., assignor to Margo Wine Company, Philadelphia, Pa., a corporation of Pennsylvania

Application October 26, 1949, Serial No. 5,716

Term of patent 14 years

(Cl. D58—8)

To all whom it may concern:

Be it known that I, John A. Margolis, a citizen of the United States of America, residing at Philadelphia, county of Philadelphia, and State of Pennsylvania, have invented a new, original, and ornamental Design for a Decanter Bottle, of which the following is a specification, reference being had to the accompanying drawing, forming a part thereof.

I claim:

The ornamental design for a decanter bottle, as shown.

JOHN A. MARGOLIS.
